UNITED STATES PATENT OFFICE

DONALD J. PHELPS, OF CHICAGO, ILLINOIS, ASSIGNOR TO PHELPS RADIO CORPORATION,
OF CHICAGO, ILLINOIS, A CORPORATION OF ILLINOIS

DESIGN FOR A RADIO CABINET

Application filed March 23, 1932. Serial No. 43,275. Term of patent 14 years.

To all whom it may concern:

Be it known that I, DONALD J. PHELPS, a citizen of the United States, residing at Chicago, Illinois, post-office address 139 N. Clark Street, Chicago, Illinois, have invented a new, original, and ornamental Design for a Radio Cabinet, of which the following is a specification, reference being had to the accompanying drawings, forming part thereof.

Fig. 1 is a front perspective view and Fig. 2 is a perspective view looking at the back of the cabinet.

I claim:
The ornamental design for a radio cabinet as shown.

DONALD J. PHELPS.
